UNITED STATES PATENT OFFICE.

WALTER I. COLBY, OF HAVERHILL, MASSACHUSETTS.

TURNED SHOE.

1,233,754.

Specification of Letters Patent.

Patented July 17, 1917.

Application filed May 16, 1917. Serial No. 169,104.

To all whom it may concern:

Be it known that I, WALTER I. COLBY, a citizen of the United States, and a resident of Haverhill, county of Essex, and State of 5 Massachusetts, have invented an Improvement in Turned Shoes, of which the following is a specification.

In the manufacture of turned shoes it has previously been customary to provide a box-10 toe-stiffener therein which merely consists of one or more sheets of textile material which is usually slightly stiffened with some form of adhesive. Such a stiffener is unsatisfactory, but the use of a more satisfactory 15 stiffener, such as leather, which is sufficiently stiff to make as strong a box as is desired, has been considered impractical on account of the fact that the shoe must be turned after the stiffener has been inserted, which 20 operation involves the turning of the stiffener. This operation on such a stiffener, while possible under some conditions has been considered impractical for a number of reasons, some of which are as follows:— 25

It is the intention, in making turned shoes, to have the shoe turned and relasted immediately after the shoe is sewed, so that this 30 may be done while the sole and counter are still in temper, but, frequently some time elapses before the turning operation is performed, so that a leather toe-stiffener, if employed, would become so dry that, either it 35 could not be turned by ordinary methods, or, if it were turned, the shoe would be spoiled or seriously damaged.

In many instances if it were attempted to retemper the stiffener by the application of water, the moisture would strike through to the upper to its finished surface, and cause 40 discolorations, which would be highly objectionable.

Furthermore, even if the shoe having a leather toe-stiffener is turned while the stiffener is still in temper, another equally serious difficulty is likely to be encountered in 45 that the turning operation tends to roll the stiffener out of position, or to form wrinkles or bunches therein, and this has usually been the result when such use of a leather toe-stiffener has been attempted. As it is difficult, and usually impossible to work the stiffener back 50 into place after such an occurrence, the use of suitably stiff, leather box-toe-stiffeners for turned shoes has not been considered 55 practical for this reason, also.

Another objection to a stiffener, which must be in temper when turned, is that the moisture therein, when properly tempered to permit turning, is liable to strike through the upper of the shoe to the finished surface, 60 so as to cause discolorations.

The use of celluloid as a toe-stiffener for turned shoes has been attempted, but as it must be softened by dipping it in alcohol before it is placed in position in the shoe and as the alcohol is liable to evaporate before the shoe is turned, this material has been found to be impractical for this purpose. 65

Other forms of toe-stiffeners have been employed for turned shoes, but any stiffener 70 which may be turned when not in temper, or which does not stiffen very substantially after it is turned, is of but slight value for this purpose. Nevertheless, leather is, so far as I am aware, the most desirable material 75 which can be employed in making a box toe-stiffener for turned shoes, provided the above difficulties can be avoided.

The object of my invention is to produce a turned shoe in which the toe-stiffener 80 thereof includes a sole-leather stiffening portion, of the desired strength, and which is incorporated therein in such a manner that the above noted objections will be avoided, so that the stiffener will not be wrinkled, or 85 otherwise misplaced by the turning operation, and may be softened or retempered with water, after the shoe is sewed, and before it is turned, without danger of injury to the upper or without danger of having 90 the moisture in the leather piece strike through to the upper, whether it is necessary to retemper it or not.

I accomplish these objects in the manner hereinafter described and as illustrated in 95 the accompanying drawing, in which:

Figures 1, 2 and 3 are longitudinal sectional views, on an enlarged scale, of the toe portion of a turned shoe, embodying my invention, and showing the shoe in progressive stages of the manufacturing process. 100

Figs. 4 and 5 are detail plan and sectional views of the stiffener, which I employ.

As illustrated in Fig. 1, when the shoe is 105 lasted, the upper *a* is drawn onto the last inside out, and temporarily held in place by two tacks at each side, and the usual cloth lining *b* is turned back to expose the flesh surface of the upper, to permit the insertion of a box-toe-stiffener therebetween, 110

which has been especially prepared for my purpose.

Each of these stiffeners which I have prepared previously, is composed of a piece of thin, textile fabric *c*, of suitable shape for a box-toe-stiffener, and having a non-waterproof adhesive applied to one side thereof, and a piece of leather *d*, of the same shape, securely cemented to the other side thereof 10 by a continuous coating *e* of rubber cement, preferably mixed with powdered cork, and adapted to provide an impermeable layer therebetween, so that water will be prevented from passing from one piece to the other.

15 The process of cementing these pieces together, with a waterproof cement, requires some time in order that the operation may be satisfactorily performed, as the cement must be applied to both surfaces and then exposed to the air, for a time, before they can be placed together. It is also necessary that the cement become thoroughly set before the stiffener is placed in the shoe. The leather piece *d* is preferably formed from 20 split sole leather, the split next the grain side being preferable in many instances, and its edge-portions are all skived down to a sharp edge, as shown.

Before the stiffener, thus prepared, is 30 placed in position on the toe of the shoe, it is dipped in water, and laid aside until the leather is thoroughly tempered. At the same time the non-waterproof cement on the textile piece *c* will be softened, so that it is 35 will adhere at once to the part to which it is applied.

When the stiffening piece, thus formed and in temper, is placed in position in the shoe, the previously prepared adhesively 40 coated surface of the textile piece is placed on the flesh surface of the upper, so that the latter will firmly adhere thereto, and then the lasting operation is finished, so that the stiffening piece is lasted in with the upper 45 and lining, as indicated in Fig. 2. The shoe is then sewed, the stitches passing through the edge of the stiffener, as well as the upper, lining, and sole, and then it is turned and relasted in the usual manner, the construction of the finished shoe being indicated in Fig. 3.

With the above described construction, the leather stiffening piece or stiffener *d* will be securely connected, throughout its 55 entire surface, to the inner surface of the upper, practically as if it were integral therewith, for the interposed textile piece *c* is securely attached at one side to the upper, and, at the other side, to the leather piece *d* 60 through the waterproof cement *e*, thereby acting as an anchoring member for the leather piece. As a result, when the turning operation is performed, the connection between the upper and the stiffener piece *d* 65 will not be broken, misplaced, or wrinkled,

as the adhesive which connects the textile piece to the upper and that which connects it to the leather as well as the textile piece itself, are all flexible, they do not interfere with the turning operation. In case, however, the leather stiffener should become too dry to be turned easily, before the shoe maker is ready to turn the shoe, the stiffener may be readily retempered, without danger of injury to the upper, by simply wetting the 70 tip portion of the cloth lining, which lies directly thereon, so that the moisture will strike through the lining to the stiffener, so as to retemper it, but will be prevented from striking through to the textile piece 75 by the waterproof layer *e* therebetween. Consequently there is no danger that the adhesive connection of the textile piece with the upper will be loosened, or that the moisture will strike through to the surface of 80 the upper, so as to damage its appearance.

The waterproof layer *e* also protects the upper from moisture in the leather stiffener, even when it is not necessary to retemper the latter before turning. 90

As above stated the rubber cement, employed to attach the textile and leather pieces together, is preferably mixed with pulverized cork. The purpose of using this substance in this relation is to increase the 95 thickness of the waterproof layer and to increase the resilience and strength of the box, so that it will better hold its shape, and be less likely to be "broken down."

I claim:

1. A turned shoe having a previous lining, a leather box-toe-stiffener disposed next the lining in position to permit the application of moisture thereto through the lining, and anchoring means for said stiffener composed of a sheet of relatively thin, flexible material adhesively connected, at one side, to the inner side of the upper, and, at the other, to said stiffener, the connecting adhesive between said sheet and stiffener being 105 of waterproof material and forming an impermeable layer therebetween, to prevent the passage of moisture from one to the other.

2. A turned shoe having a textile lining, a leather toe-stiffener disposed next the lining, a textile sheet adhesively connected to the inner side of the upper and a layer of waterproof material adhesively connecting said leather stiffener and textile piece. 115

3. A turned shoe having a textile lining 120 and provided with a leather toe-stiffener, disposed next the lining, and a textile sheet for said stiffener, coextensive therewith, and adhesively connected, at one side, to the inner side of the upper and, at the other, to 125 said stiffener, the connecting adhesive between said sheet and said stiffener consisting of an impermeable layer of waterproof material.

4. A turned shoe having a textile lining 130

- and provided with toe-stiffening means comprising a leather stiffener having one surface thereof disposed next the lining, and a textile sheet having one surface thereof adhesively connected to the inner surface of the upper, and having an impermeable layer of waterproof adhesive, mixed with pulverized cork, connecting the other surface thereof with the other surface of said stiffener.
- 5 10 5. A box-toe-stiffener for turned shoes comprising a leather stiffening piece, and anchoring means therefor consisting of a sheet of relatively thin, flexible material having a waterproof coating on one of its surfaces, adhesively to connect it to one surface of the stiffening piece and prevent the passage of moisture from one to the other, and having a non-waterproof adhesive on its
- 15

other surface, to connect it to the inner surface of the shoe upper, when moistened. 20

6. A box-toe-stiffener for turned shoes consisting of a leather stiffening piece, a textile sheet extending over one side thereof, a sheet of waterproof material adhesively connecting said stiffening piece and said textile 25 sheet and forming an impermeable layer therebetween, and a non-waterproof adhesive on the opposite side of said textile sheet from said stiffening piece for connecting said sheet to the inner surface of the upper. 30

In testimony whereof, I have signed my name to this specification.

WALTER I. COLBY.

Witness:

L. H. HARRIMAN.
